(57) **CLAIM**

The ornamental design for a charger holder as shown and described.

DESCRIPTION

FIG. 1 is a front perspective view of a charger holder showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of an indicated portion of FIG. 3;

FIG. 10 is an alternate front perspective view of the charger holder, showing its ability to connect to a power adapter and hold a radio communicator;

FIG. 11 is an alternate rear perspective view thereof;

FIG. 12 is an alternate front view thereof;

FIG. 13 is an alternate rear view thereof;

FIG. 14 is an alternate left side view thereof;

FIG. 15 is an alternate right side view thereof;

FIG. 16 is an alternate top view thereof; and,

FIG. 17 is an alternate bottom view thereof.

The broken lines in FIGS. 1-17 illustrate portions of the charger holder that form no part of the claimed design. The dot-dash broken lines in FIGS. 1-7 and 10-16 represent a boundary and forms no part of the claimed design. The broken lines in the form of a power adapter and a radio communicator in FIGS. 10-17 depict environmental subject matter and form no part of the claimed design.

1 Claim, 12 Drawing Sheets
